United States Patent

Des. 241,850
Patented Oct. 12, 1976

241,850

BUILDING

Jeffrey L. Wachter, Box 838, Bismarck, N. Dak. 58501

Filed Sept. 11, 1974, Ser. No. 504,866

Term of patent 14 years

Int. Cl. D25—03

U.S. Cl. D25—18

FIG. 1 is a view in perspective as seen from the front and side of a building showing my new design;

FIG. 2 is a view in perspective as seen from the front, side and top thereof;

FIG. 3 is a view in top plan thereof;

FIG. 4 is a view in side elevation thereof as seen from the side opposite that shown in FIG. 1;

FIG. 5 is a view in front elevation thereof; and

FIG. 6 is a view in rear elevation thereof.

The bottom not shown is devoid of ornamentation.

I claim:

The ornamental design for a building, substantially as shown and described.
